UNITED STATES PATENT OFFICE.

FÉLIX JULES BOSSET AND PHILIPPE CACHARD, OF LYON, FRANCE, ASSIGNEES TO SOCIÉTÉ ANONYME DES ANCIENS ÉTABLISSEMENTS BOSSET ET CACHARD, OF LYON, FRANCE.

LOOM.

1,009,041.

Specification of Letters Patent. Patented Nov. 21, 1911.

Application filed July 18, 1910. Serial No. 572,612.

To all whom it may concern:

Be it known that we, FÉLIX JULES BOSSET and PHILIPPE CACHARD, citizens of the French Republic, residing at Lyon, in France, have invented a certain new and useful Improvement in Looms, of which the following is a specification.

The present invention relates to a loom for simultaneously weaving a plurality of webs with free selvages.

To this end a special disposition of the warp threads is adopted, so that at least two pieces of fabric are simultaneously woven side by side.

15 The improved loom in its most simple form comprises two shuttles moving simultaneously in the same direction, and three pickers, two at the ends of the lay and another at the center, acting alternately on both shuttles. The use of the central picker is rendered possible by a special stop-motion device at the central shuttle box, which becomes alternately operative, according as the right hand or the left hand 25 shuttle enters the box.

The invention also comprises special means for regulating the winding of the several webs. Both the webs are simultaneously drawn along, but they may be wound 30 at the same speed or at different speeds, the latter being, for instance, the case when the "reduction" of the two pieces is not the same.

The invention also comprises certain other 35 features and devices connected with the operation and control of the loom, all of which will now be particularly described with reference to the accompanying drawings.

The drawings show by way of example a 40 loom for simultaneously weaving four webs, in two planes one above the other.

In the drawings Figure 1 is a front elevation of the machine, Fig. 2 a side view, Fig. 3 a vertical section on the line 3—3 of 45 Fig. 1, and Fig. 4 is a cross-section on the line 4—4 of Fig. 1, Fig. 5 is a front view, on a larger scale, of the mechanism for actuating the picker of the central shuttle box, Fig. 6 a side view thereof, and Fig. 7 a 50 plan view. Fig. 8 is an elevation of the central shuttle box, with its driver, Fig. 9 a plan view thereof, partly in section on the line 9—9 of Fig. 8, and Fig. 10 a rear view. Fig. 11 is a cross-section of the said shuttle 55 box, on the line 11—11, of Fig. 10. Fig.

12 is a perspective elevation of the driver of the central shuttle box.

In Fig. 1, A A are the posts of the frame, connected to each other by beams B. One of the latter supports four standards A¹, 60 which have bearings for the upper cloth beams K of four pairs of cloth beams K, L, two at each side of the vertical median plane, arranged as shown in Fig. 4, the lower cloth beams L being supported by 65 pivoted forks L¹. C, C, are warps drawn off beams D, and C¹, C¹, are the webs. E represents the heddles and F the lay, the swords F¹ of which support the shuttle boxes G, G, and g. The cranked shaft M 70 rocks the lay and imparts rotation to the cam-shaft P which actuates the picker staffs J, J, and j pivoted to holders S, S, s on the rock shaft T to which the swords of the lay are fixed. All these parts are of 75 known type.

I. *Regulator of take-up motion.*—To the shaft T is fixed a V-shaped lever V. Upon the apex of this lever rests a vertically slidable rod W, to which is fixed a star-shaped 80 piece w carrying four pawls X, each engaged with a ratchet wheel Y. The rocking movement of the shaft T and lever V reciprocates the rod W and causes the ratchet wheels Y to be rotated by the pawls X. The 85 spindles of the ratchet wheels Y are provided with worms y gearing with worm wheels Z, which are keyed to the gudgeons Z¹ of the cloth beams K. The webs travel over the beams K and then on to the beams L, on which they are wound, the beams L with the cloth thereon being thrust firmly 90 against the beams K. All the beams K rotate simultaneously, at a speed which depends in the case of each beam K, on the 95 amplitude of the movement of the rod W and on the diameter of the respective ratchet wheel Y. The movement of the rod W being constant, the speed of each beam K depends in practice on the diameter of the 100 ratchet wheel Y, so that the speeds of the beams can be changed independently of each other by changing the wheels Y. In this way the beams are caused to rotate more or less quickly according to the required "reduction." The result obtained with this mechanism is equal to that obtained with four ordinary take-up regulators, though the former comprises fewer parts.

II. *Picker-motion.*—The picker staffs J of 110

- the lateral shuttle boxes are actuated by cams Q which operate rocking arms R. The central shaft *j*, acting alternately on the shuttles at the right and at the left, is actuated by a single cam *q* and the mechanism shown in Figs. 5, 6 and 7. The cam *q* is a box cam, engaged with a roller 1 pivoted to an arm 2 fixed to one end of a shaft 3, to the other end of which is fixed a rock-arm 4.
- 10 The arm 4 is laterally enlarged at its upper end, as best shown in Fig. 7, and carries two rounded abutments 7 resting upon rollers 6 mounted upon arms of a socket 5 by means of which the staff *j* is connected to its holder *s*.
- 15 The purpose of the rollers 6 is to reduce the friction due to the forward and rearward rocking movement which is imparted to the staff socket, in addition to lateral rocking movement, to enable the staff to follow the 20 movements of the lay. The cam *q* imparts two effective strokes to the picker staff 12 at each stroke of the lay.
- III. *Central shuttle-box and stop-motion mechanism.*—The central shuttle-box *g* is 25 open at both ends and comprises two compartments *g*¹ and *g*², located one above the other. The stop-motion mechanism is of the type which acts automatically when either of the shuttles fails to arrive in the box toward which it has been driven. Each of the 30 lateral shuttle-boxes *G* is provided with a device *G*¹ (Figs. 1 and 2) of known type, for this purpose, and the central shuttle-box is provided with shuttle-operated mechanism 35 which can be adjusted so as to alternatively disable either of the lateral stop-motion devices, the adjustment being automatically effected during the working of the loom so 40 that said disabling mechanism always disables the stop motion at the lateral box whence the shuttles have arrived. This mechanism is shown in Figs. 8, 9, 10 and 11.
- At the rear of the box 9 a bar 19, bifurcated at its ends, is reciprocatable by means of 45 a lever 29 rocking as indicated by arrows *a b* in Fig. 10. Two pairs of abutment levers 13 and 14 are hinged to the ends of this bar 19, by means of pivots 20, and these levers have bosses 13^a and 14^a protruding 50 through slots 15 and 16 into the upper and lower compartments of the box *g*. Said levers also have bosses 17, 17 and 18, 18 at the rear, adapted to coact with two pairs of rollers 27 and 28, the rollers 27 and 28 being 55 mounted, respectively, on the ends of double armed levers 25 and 26 pivoted to curved arms 23 and 24 fixed to stop-motion spindles 21 and 22 respectively. The latter extend to the lateral shuttle-boxes *G G*.
- 60 The bar 19 is reciprocated synchronously with the picker motion, but moves to the left while the picker staff *j* is moving to the right, and vice versa. When the bar 19 moves in the direction of the arrow *b* (Fig. 65 10) the rollers 28 are thrust to the rear by

the bosses 18. When thereupon the shuttles enter the box, and act on the bosses protruding thereinto, they rock the spindle 22 by means of the rollers 28, and the checking dog of the spindle 22 is lifted, but the spindle 21 is not similarly operated, owing to the fact that the rollers 27 are not on the bosses 17, and the checking dog of this spindle 21 will stop the loom unless said spindle has been operated by the arrival of shuttles in the box *G* at its opposite end.

If one of the shuttles fails to arrive in the box *g*, one of the rollers 18 will not be thrust back, so that the lever 26 will rock on its pivot on the arm 24, and the dog will cause the loom to stop.

When the bar 19 is moved in the direction of arrow *a*, the rollers 27 ride on to the bosses 17, and are ready for actuation by the shuttles arriving from the opposite direction.

The lever 29 is pivoted to a beam 30 (Fig. 3) fixed to the swords of the lay, and is rocked by engagement with the arm 4 already described.

90 The driver 12 in the box *g*, best shown in Fig. 12, is approximately H-shaped, comprising two vertical limbs 31 and 32 with curved inner surfaces, fixed into a slotted cross-bar 36. Blocks 33 and 34 are fixed to the upper and lower ends of the said limbs, and are respectively located in the upper and lower compartments of the box *g* (Fig. 11). The box *g* has a slot 35 for the picker-staff *j*, and the latter engages the slotted bar 12 between the two limbs 31 and 32 of the driver.

95 Each vertical limb of the shuttle acts in turn on two shuttles, by means of the blocks 33 and 34, which act with equal force, driving the shuttles with uniform speed. If there are more than two compartments in the shuttle-box *g* the limbs 31 and 32 are lengthened and provided with additional blocks for driving shuttles.

100 It will be clear that without departing from the principle of the invention the loom may be constructed to simultaneously weave six, eight and any other even number of webs.

110 What we claim as our invention and desire to secure by Letters Patent of the United States is:—

1. In a loom the combination of a lay, a central shuttle-box on said lay, lateral shuttle-boxes, one at each end of said lay, automatic stop-motion devices at the lateral shuttle-boxes, a shuttle-operated stop-motion disabling device, and means for automatically adjusting said disabling device so that actuation thereof by a shuttle arriving at the central box from either side of the loom disables the stop-motion device at the lateral box whence said shuttle has arrived.
2. In a loom the combination of a lay, a

- central shuttle box on said lay, lateral shuttle-boxes, one at each end of said lay, automatic stop-motion devices at the lateral shuttle-boxes, stop-motion disabling levers, 5 one for each stop motion device, a shuttle-operated abutment device at the central shuttle-box, adjustable by reciprocation so that it can be placed in operative relation with either of said disabling levers, and 10 means for automatically reciprocating said abutment device so that actuation thereof by a shuttle arriving from either side of the loom disables the stop motion device at the lateral box whence said shuttle has arrived.
- 15 3. In a loom the combination of a lay, a central shuttle box on said lay, lateral shuttle-boxes, one at each end of said lay, automatic stop-motion devices at the lateral shuttle-boxes, stop-motion disabling levers, 20 one for each stop motion device, a shuttle-operated abutment device at the central shuttle-box, adjustable by reciprocation so that it can be placed in operative relation with either of said disabling levers, a picker- 25 staff at the central shuttle-box, and means for collectively actuating said staff and reciprocating said abutment device so that actuation of the latter by a shuttle arriving from either side of the loom disables the 30 stop motion device at the lateral box whence said shuttle has arrived.
4. In a loom the combination of a lay, a central shuttle box on said lay, lateral shuttle-boxes, one at each end of said lay, automatic stop-motion devices at the lateral shuttle-boxes, stop-motion disabling levers, 35 one for each stop motion device, a shuttle-operated abutment device at the central shuttle-box, adjustable by reciprocation so that it can be placed in operative relation with either of said disabling levers, a picker-staff at the central shuttle-box, a rock-shaft, a 40 rock-arm for rocking said picker staff, and a lever engaged with said abutment device and said rock-arm, whereby said abutment device is 45 adjusted in relation to the disabling levers so that actuation of said abutment device by a shuttle arriving from either side of the loom disables the stop motion device at the 50 lateral box whence said shuttle has arrived.
5. In a loom the combination of a lay, a central shuttle box on said lay, lateral shuttle-boxes, one at each end of said lay, auto- 55 matic stop-motion devices at the lateral shuttle-boxes, stop-motion disabling levers, 60 one for each stop motion device, a shuttle-operated abutment device at the central shuttle-box, adjustable by reciprocation so that it can be placed in operative relation with either of said disabling levers, a picker-staff 65 at the central shuttle box, a rock-shaft, a picker-staff holder having lateral arms, and pivoted to said rock-shaft to enable it to drive while rocking with the lay, anti-friction rollers on said lateral arms, a T-shaped rock-arm engaging said rollers, means for actuating said rock-arm, and a lever engaged with said abutment device and said rock-arm, whereby said abutment device is 70 adjusted in relation to the disabling levers 75 so that actuation of said abutment device by a shuttle arriving from either side of the loom disables the stop motion device at the lateral box whence said shuttle has arrived.
6. In a loom the combination of a lay, a central shuttle box on said lay, lateral shuttle-boxes, one at each end of said lay, automatic stop-motion devices at the lateral shuttle-boxes, stop-motion disabling levers, 80 one for each stop motion device, a shuttle-operated abutment device at the central shuttle-box, adjustable by reciprocation so that it can be placed in operative relation with either of said disabling levers, a picker-staff at the central shuttle-box, a rock-shaft, a 85 picker-staff holder having lateral arms, and pivoted to said rock-shaft to enable it to drive while rocking with the lay, antifriction rollers on said lateral arms, a T-shaped rock-arm engaging said rollers, box-cam 90 mechanism for actuating said rock-arm, and a lever engaged with said abutment device and said rock-arm, whereby said abutment device is 95 adjusted in relation to the disabling levers so that actuation of said abutment device by a shuttle arriving from either side of the loom disables the stop motion device at the lateral box whence said shuttle has arrived.

In witness whereof we have signed this 100 specification in the presence of two witnesses.

FÉLIX JULES BOSSET.
PHILIPPE CACHARD.
